UNITED STATES PATENT OFFICE

WILLIAM A. SMITH, JR., OF PHILLIPSBURG, NEW JERSEY, ASSIGNOR TO INGERSOLL-RAND COMPANY, OF JERSEY CITY, NEW JERSEY, A CORPORATION OF NEW JERSEY

VALVE FOR ROCK DRILLS

Application filed December 8, 1928. Serial No. 324,725.

This invention relates to rock drills, but more particularly to a valve for effecting the distribution of pressure fluid to the cylinder of the rock drill of the hammer type.

5 The objects of the invention are to insure a steady and positive action of the valve, and to provide a substantially direct path from the source of pressure fluid supply to the ends of the cylinder.

10 Other objects will be in part obvious and in part pointed out hereinafter.

In the drawings illustrating the invention and in which similar reference characters refer to similar parts,

15 Figure 1 is a sectional elevation of so much of a rock drill as will serve to illustrate the invention, and

20 Figure 2 is a transverse view taken through Figure 1 on the line 2—2 looking in the direction indicated by the arrows.

25 Referring more particularly to the drawings, A represents the cylinder of a rock drill having in this instance a free exhaust port B for conveying fluid from a piston chamber C in the cylinder. A reciprocating hammer piston D is disposed in the piston chamber C and carries a fluted extension E which extends in a forwardly direction to deliver blows of impact to a working implement (not shown) and is guided by a bore F of a front cylinder washer G which serves as a closure for the front end of the piston chamber C.

30 In the rearward end of the cylinder A is an enlarged bore H for the reception of a valve chest designated generally by J. The valve chest J comprises a pair of plates K and L. The plate L occupies the extreme innermost position in the bore H and acts as a closure for the rearward end of the piston chamber C. The plate J is seated on the plate L and in turn acts as a seat for a rotation ratchet O disposed in the rearward end of the bore H.

35 The rotation ratchet O may be of a well known type and is provided with the usual teeth P to serve as abutments for spring pressed pawls F carried by the head R of a rifle bar S. The rifle bar S extends through the plates K and L and is suitably fluted for

slidable engagement with the piston D, as is the usual practice.

Disposed at the rearward end of the cylinder A and seated on the rotation ratchet O is a back head T which may be secured to the cylinder in any suitable manner as for instance by the usual spring pressed side bolts (not shown) but which side bolts also serve to clamp the rotation ratchet O and the valve chest J fixedly in the bore H.

40 The back head T has a throttle valve chamber U for a throttle valve V whereby the admission of pressure fluid into the drill may be controlled. The throttle valve V as illustrated is of the rotary type and is accordingly provided with a lever W whereby it may be manipulated. The pressure fluid may be introduced into a central chamber X in the throttle valve which may be in constant communication with the pressure fluid supply. 45 In the wall of the throttle valve V is a port Y which in the open position of the throttle valve registers with a passage Z leading to a supply reservoir b in the front end of the back head T.

45 The plate L is recessed to form a valve chamber e, the opposite ends d and e of which communicate with the supply reservoir b through supply passages f and g respectively and extending through the plate 50 K and the rotation ratchet O.

55 The valve chamber e is intended to accommodate a distributing valve h of the oscillatory plate type having a central fulcrum j whereon said valve is adapted to rock from one limiting position to the other. The pressure fluid distributed by the valve h flows into the rearward end of the piston chamber C through an inlet passage k in the plate L and into the front end of the piston chamber 60 C through an inlet passage o formed in the plate L and the wall of the cylinder A.

65 The contiguous surfaces of the plates L and K serve as seating surfaces p and q against which the opposite sides of the valve 65 h may seat. In the seating surface p and surrounding the inlet openings of the passages k and o are grooves r and s which serve to minimize the area of contact between the seating surface p and the forward surfaces 70

of the wings *t* and *u* of the valve, and also to act as pressure chambers into which pressure fluid may be admitted to act against the forward surfaces of the wings *t* and *u* for actuating the valve.

In valves of this type as heretofore constructed, it has been customary to permit the pressure fluid to flow over the edges of the raised portions of the wings of the valve during its course to the cylinder. While this method has been reasonably satisfactory, it involves a degree of accuracy in the machining of the valve and a delicate balance and apportionment of areas which greatly adds to the cost of manufacturing. In certain cases it has also been found that when thus constructed the suction created by the pressure fluid during the course over the raised end of the valve tended to slightly raise the seated end of the valve and thus admit a portion of pressure fluid into the piston chamber in advance of the piston. The result was that this leakage of pressure fluid, coupled with the compression, created by the piston, absorbed some of the force of the blow and, while not causing the piston to short stroke, it would however at times decrease the drilling efficiency considerably.

The present invention particularly aims to eliminate the foregoing objectionable feature and to this end the valve *h* is provided in its wings *t* and *u* with ports *v* and *w* respectively. There may be one or more of these ports depending upon the number of supply passages, three are shown in this instance in each wing for the purpose of illustration, and said port or ports are so located in the wings that they will register with the supply passages to admit pressure fluid from the supply reservoir *b* into the forward end of the valve chamber *c*, from whence the pressure fluid will flow through the inlet passages *k* and *o* into the ends of the piston chamber.

The ports *v* and *w* are also preferably of somewhat larger cross sectional area than the supply passages wherewith they are adapted to register so that the pressure fluid during its course through the valve will in no wise exert a force thereon tending to tilt it from its limiting position. In other words only those forces which act in proper sequence and are dependent on the movement of the piston *D* will be effective to actuate the valve.

The seating surfaces *p* and *q* are so spaced that the opposite sides of the wings *t* and *u* may lie flush thereagainst. In this way when the wings are raised, their rearward surfaces will lie snugly against the seating surface *q* so that there will be no pressure fluid between the rearward surfaces of the valve and the seating surface *q*.

As will be observed, the inlet openings of the inlet passages *k* and *o* lie in different planes from the outlet openings of the sup-

ply passages *f* and *g* and the ports *v* and *w* register only with the supply passages and with the grooves *r* and *s*.

The operation of the device is as follows: With the throttle valve *v* in the open position illustrated, pressure fluid will flow therefrom through the passage *Z* into the supply reservoir *b*, thence through the supply passage *g* into the valve chamber *c*. With the valve occupying the position illustrated, pressure fluid will flow through the raised wing *t*, that is, through the ports *v* into the front end of the valve chamber *c* and thence through the inlet passage *k* into the rearward end of the piston chamber *C* to drive the piston *D* forwardly. At the same time pressure fluid will occupy the opposite end *d* of the valve chamber and will press against the rearward surface of the wing *u* to hold the valve firmly seated. This pressure however, is augmented by that flowing from the opposite end *e* of the valve chamber and acting against the forward surface of the wing *t*. Although pressure fluid will flow through the port *w* into the groove *s* to act against a portion of the forward surface of the wing *u*, this pressure will not be effective to in any way disturb the position of the valve.

As the piston *D* proceeds forwardly, the free exhaust port *B* will be covered thereby and from that point on the air in the front end of the piston will be compressed and will flow through the inlet passage *o* to act against an area of the forward surface of the wing *u* equal to the cross sectional area of the inlet passage *o*. As the piston *D* continues forwardly, it will overrun the free exhaust port *B* and the fluid utilized for actuating it forwardly will then be exhausted to the atmosphere. This will cause an abrupt drop in pressure beneath the wing *t* and the force of the compression in the inlet passage *o* and the pressure fluid in the groove *s* will then tilt the valve to its other extreme position.

In the new position of the valve, the inlet passage *k* will be covered by the wing *t* and the port *w* will be in registry with the supply passage *f* so that pressure fluid may flow directly through these channels from the supply reservoir *b* into the front end of the valve chamber and thence through the inlet passage *o* into the front end of the piston chamber *C* to drive the piston *D* rearwardly.

During the rearward course of the piston *D*, the air in the rearward end of the piston chamber *C* will be compressed to act against the seated wing *t* and after the piston *D* uncovers the free exhaust port *B* the compression in the rearward end of the piston chamber and the pressure fluid in the grooves *r* will again tilt the valve *h* to its initial position.

I claim:
In a fluid actuated rock drill, the combi-

nation of a cylinder and a piston, an exhaust port for the cylinder, a valve chest comprising a pair of plates forming a valve chamber, seating surfaces on the contiguous 5 portions of the plates, supply passages in one plate for conveying pressure fluid to one end of the valve chamber, inlet passages in the other plate for conveying pressure fluid from the valve chamber to the cylinder, pressure 10 chambers in the second said plate dissociated from the inlet passage, an oscillatory plate valve in the valve chamber having a pair of wings to control the inlet passages, said wings being adapted to seat against the seating 15 surfaces of both plates, and a port in each wing to register with the supply passages and through which pressure fluid flows into the valve chamber for supplying the inlet passages in one position of the valve and to register 20 with the pressure chambers in another position of the valve for supplying pressure fluid to said pressure chambers to assist in throwing the valve.

In testimony whereof I have signed this 25 specification.

WILLIAM A. SMITH, JR.
